UNITED STATES PATENT OFFICE

2,168,727

BLIND STITCH SEWING MACHINE

Louis G. Bowman, St. Louis, Mo., assignor to
 Lewis Invisible Stitch Machine Company,
 St. Louis, Mo., a corporation of Maine

Application April 29, 1937, Serial No. 139,809

20 Claims. (Cl. 112—176)

This invention relates to improvements in blind stitch sewing machines generally, although more particularly to the presser feet thereof, and embodies certain improvements over Patent 5 1,740,901, issued December 24, 1929, to Charles W. Mueller.

Heretofore, when operating a machine as shown in said patent, for sewing sleeve linings to a coat, it was customary for the operator when 10 operating on one side of the coat to sew the main lining to the body fabric from the bottom of the coat to the arm hole, and on the other side of the coat to sew the main lining to the body fabric from the arm hole to the bottom of the coat; 15 that is, stitch the main lining to the body fabric along the entire side seams of the coat. This method necessitated the employment of a hand sewer to rip the stitches where the main lining is attached to the sweat shield at each side of the 20 coat at the upper portion of each side seam adjacent the arm hole in order to insert the sleeve lining, and then fell by hand around each arm hole.

The principal object of my invention is to provide 25 a presser foot by means of which the cost of the above described operation will be reduced and the production will be increased.

Another object of the invention is to provide 30 an attachment to the presser foot of said prior patent construction, whereby the operator can sew the main lining to the sweat shield only and thereby avoid stitching the body fabric for a short distance, say about two inches, thereby 35 allowing the hand sewer to sew only the sleeve lining to the main lining without having to rip the stitches for said short distance.

With these and other objects in view which 40 will more fully appear, the nature of the invention will be more clearly understood by following the description, the appended claims, and the several views illustrated in the accompanying drawings.

In the drawings:

Figure 1 is a top plan view of the presser foot 45 showing the interponent in its operative position.

Figure 2 is a partial top plan view of the presser foot showing the interponent in its inoperative position.

Figure 3 is a bottom plan view of the presser 50 foot showing the interponent in its inoperative position.

Figure 4 is an enlarged right hand elevation of the presser foot.

Figure 5 is an enlarged front elevation of the 55 presser foot.

Figure 6 is a transverse sectional view taken on the line 6—6 of Figure 1.

Figure 7 is a perspective view of the shiftable interponent assembly,

Figure 8 is a diagrammatic view showing the 5 relation between the ridge forming element, the fabrics, the needle, the vertically adjustable crown, the adjustable stop for limiting the upward movement of the crown, and the interponent in its normal or inoperative position between the crown and the adjustable stop, and

Figure 9 is a similar view but showing the interponent in its operative position between the crown and the adjustable stop.

Like reference numerals designate corresponding 15 parts throughout the several figures of the drawings.

The presser foot A which embodies my invention, includes a heel 5 and a toe 6, and is provided with an opening 7 located therebetween and 20 through which the superposed fabrics B, C are projected upwardly by a vertically yieldable ridge forming element D into position to be penetrated by the needle E. The needle E, as in the Mueller Patent 1,740,901, oscillates about a fixed axis 25 located above the opening 7 and has its path of movement in the line of feed, and the foot is retained in a stationary manner on the machine frame, the toe 6 of the foot, immediately in front of the opening 7, is provided with a needle 30 guide 8.

Formed in the under face of the foot and on the right hand side of the opening, is a transverse recess 9 in which is mounted a crown F. The inner end of the crown projects into said 35 opening 7 above the ridge forming element D and is recessed to receive said element and the ridge of fabrics B, C, the inner end of the element terminating short of the needle path whereby the needle may pass above the element and at the 40 left of the crown. The outer end of the crown is provided with a rigid arm 10 which extends rearwardly along the right hand edge 11 of the presser foot and is pivoted to the latter by a screw 12 whereby the crown may have a vertical 45 movement.

A vertically adjustable stop screw G having a rounded lower end 14 is threaded directly above the crown and functions 50 to variably limit the upward movement of said crown.

A manually operable lever H extends rearwardly along the right hand side of the foot and has its rear end positioned between laterally extending ears 15, 15 integral with the crown arm 55

10 and fulcrumed thereto by a vertical screw 16.

An interponent I is provided at its outer end with a transverse slot 17, and a pivot pin 18 which is mounted on the lever H passes through said slot. The inner end of the interponent has its upper face beveled as at 19 to form a wedge shape. The interponent projects towards the stop screw G and is guided by a slot 20 formed in the front end of the crown arm 10, the slot forming a resultant finger 21 thereabove, and the latter having a beveled outer corner 22 along its upper edge. It will, therefore, be seen that when the lever H is moved inwardly towards the foot, the wedge shaped inner end of the interponent 15 will enter between the rounded lower end of the stop screw G and the crown F and depress the latter against the upwardly spring pressed ridge forming element D.

A spring latch or finger J which is secured to 20 the lever H by the pin 18, overlies the interponent I, and is provided with a downwardly inclined inner end 23. When the lever is moved inwardly the inner end 23 will engage the beveled corner 22 of the finger 21 and cam over the same to 25 thereby retain the interponent in its operative position.

In order to limit the inward movement of the interponent I and thereby variably limit the depression of the crown F whereby a predetermined 30 depth of needle penetration in the fabric may be obtained, I have provided the lever H with an adjustable stop screw K which engages the adjacent side face of the foot when said lever is swung inwardly.

35 In order to limit the outward swinging movement of the lever H and thereby retain the interponent in the guiding slot 20, I have provided the lever with an arm 24 which extends rearwardly beyond the lever fulcrum 16 for contact with 40 the head of the screw 12.

It is to be understood that the vertically yieldable ridge forming element D is moved upwardly and downwardly in suitably timed relation with the needle reciprocations by mechanism not 45 shown but which is well known in the art. The particular means for operating the element D forms no part of the present invention, and since an example of mechanism of this character is to be found in the Charles W. Mueller Patent 50 1,740,901 hereinbefore referred to, detailed description thereof herein is deemed unnecessary.

From the foregoing, it will be seen that superposed fabrics B, C are fed rearwardly below the needle path, and that the ridge forming element 55 D projects a ridge of said fabrics upwardly through the presser foot opening into needle penetrating position. When the interponent I is in its normal or inoperative position as shown in Figure 8, the stop screw G is first adjusted vertically whereby the needle will engage both fabric layers. Whenever, it is desirable to lessen the depth of needle penetration whereby the needle 60 will engage the superposed layer only, the lever H is swung inwardly to effect a depression of the crown F as shown in Figure 9 together with both fabrics and the ridge forming element D. Whenever it is desirable to return the crown to its initial position and thereby have the needle engage both fabrics, the lever is swung to the 65 right and the interponent is withdrawn to its inoperative position as shown in Figure 8 whereby the spring pressed ridge forming element will return the crown to its initial position against the stop screw.

70 75 It is of course to be understood that the de-

tails of structure and arrangement of parts may be variously changed and modified without departing from the spirit and scope of my invention.

I claim:

1. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a vertically movable crown mounted on the foot to limit the upward movement of the ridge forming element, a stop mounted on the foot to limit the upward movement of the crown, and a manually operable interponent supported on the foot and movable to a position between the stop and the crown to depress the latter and thereby reduce the depth of needle penetration in the fabric. 5 10 15

2. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a vertically movable crown mounted on the foot to limit the upward movement of the ridge forming element, a stop mounted on the foot to limit the upward movement of the crown, and a manually operable interponent supported on the foot and movable to a position between the stop and the crown to depress the latter and thereby reduce the depth of needle penetration in the fabric, said interponent being movable in a horizontal plane and provided with a wedge-shaped inner end for entering between the stop and the crown. 20 25 30

3. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a vertically movable crown mounted on the foot to limit the upward movement of the ridge forming element, a stop mounted on the foot to limit the upward movement of the crown, a manually operable interponent supported on the foot and movable to a position between the stop and the crown to depress the latter and thereby reduce the depth of needle penetration in the fabric, and adjustable means for limiting the movement of the interponent and thereby variably limit the downward movement of the crown. 40 45 50 55

4. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a vertically movable crown mounted on the foot to limit the upward movement of the ridge forming element, a stop mounted on the foot to limit the upward movement of the crown, a manually operable interponent supported on the foot and movable to a position between the stop and the crown to depress the latter and thereby reduce the depth of needle penetration in the fabric, and a spring latch for retaining the interponent in its operative position. 60 65 70

5. In a blind stitch sewing machine, the combination with a stationary presser foot having an opening, of a reciprocatory needle operating above said opening, a vertically yieldable ridge 75

5 forming element located below said opening for projecting a ridge of fabric upwardly into needle penetrating position, a vertically movable crown mounted on the foot to limit the upward movement of the ridge forming element, a vertically adjustable stop mounted on the foot to limit the upward movement of the crown, and a manually operable interponent supported on the foot and movable to a position between the stop and the crown to depress the latter and thereby reduce the depth of needle penetration in the fabric.

6. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a vertically movable crown mounted on the foot to limit the upward movement of the ridge forming element, a stop mounted on the foot to limit the upward movement of the crown, a manually operable lever mounted on the foot to swing about a vertical fulcrum, and an interponent connected to said lever and movable to a position between the stop and the crown to depress the latter and thereby reduce the depth of needle penetration in the fabric.

7. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a vertically movable crown mounted on the foot to limit the upward movement of the ridge forming element, a stop mounted on the foot to limit the upward movement of the crown, a manually operable lever mounted on the foot to swing about a vertical fulcrum, an interponent connected to said lever and movable to a position between the stop and the crown to depress the latter and thereby reduce the depth of needle penetration in the fabric, said interponent being provided with a wedge-shaped inner end for entering between the stop and the crown, and an adjustable stop mounted on the lever for cooperation with the foot to limit the inward movement of the interponent to thereby variably limit the downward movement of the crown.

8. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a vertically movable crown mounted on the foot to limit the upward movement of the ridge forming element, a stop mounted on the foot to limit the upward movement of the crown, a manually operable lever mounted on the foot to swing about a vertical fulcrum, an interponent connected to said lever and movable to a position between the stop and the crown to depress the latter and thereby reduce the depth of needle penetration in the fabric, said interponent being provided with a wedge-shaped inner end for entering between the stop and the crown, an adjustable stop mounted on the lever for cooperation with the foot to limit the inward movement of the interponent to thereby variably limit the downward movement of the crown, and a spring latch mounted on the lever for cooperation with the foot for retaining the interponent in its operative position.

9. In a blind stitch sewing machine, the com-

bination with a stationary presser foot having an opening, of a reciprocatory needle operating above said opening, a vertically yieldable ridge forming element located below said opening for projecting a ridge of fabric upwardly into needle penetrating position, a crown located above the ridge forming element to limit the upward movement thereof, an arm rigidly connected with the crown and having pivotal connection with the foot, a vertically adjustable stop screw mounted on the foot to limit the upward movement of the crown and provided with a rounded lower end, a manually operable lever pivoted on the foot to swing about a vertical fulcrum, and an interponent connected to said lever and movable to a position between the stop and the crown to depress the latter and thereby reduce the depth of needle penetration in the fabric, said interponent being provided with a wedge-shaped inner end for entering between the stop and the crown.

10. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a crown located above the ridge forming element to limit the upward movement thereof, an arm rigidly connected with the crown and having pivotal connection with the foot, a vertically adjustable stop screw mounted on the foot to limit the upward movement of the crown and provided with a rounded lower end, a manually operable lever pivoted on the foot to swing about a vertical fulcrum, an interponent connected to said lever and movable to a position between the stop and the crown to depress the latter and thereby reduce the depth of needle penetration in the fabric, said interponent being provided with a wedge-shaped inner end for entering between the stop and the crown, and an adjustable stop mounted on the lever for cooperation with the foot to limit the inward movement of the interponent to thereby variably limit the downward movement of the crown.

11. In a blind stitch sewing machine, the combination with a stationary presser foot having an opening, of a reciprocatory needle operating above said opening, a vertically yieldable ridge forming element located below said opening for projecting a ridge of fabric upwardly into needle penetrating position, a crown located above the ridge forming element to limit the upward movement thereof, an arm rigidly connected with the crown and having pivotal connection with the foot, a vertically adjustable stop screw mounted on the foot to limit the upward movement of the crown and provided with a rounded lower end, a manually operable lever pivoted on the foot to swing about a vertical fulcrum, an interponent connected to said lever and movable to a position between the stop and the crown to depress the latter and thereby reduce the depth of needle penetration in the fabric, said interponent being provided with a wedge-shaped inner end for entering between the stop and the crown, and a spring latch mounted on the lever for cooperation with the foot for retaining the interponent in its operative position.

12. In a blind stitch sewing machine, the combination with a stationary presser foot having an opening, of a reciprocatory needle operating above said opening, a vertically yieldable ridge forming element located below said opening for projecting a ridge of fabric upwardly into needle

75

penetrating position, a crown located above the ridge forming element to limit the upward movement thereof, an arm rigidly connected with the crown and having pivotal connection with the foot, a vertically adjustable stop screw mounted on the foot to limit the upward movement of the crown and provided with a rounded lower end, a manually operable lever pivoted on the foot to swing about a vertical fulcrum, an interponent connected to said lever and movable to a position between the stop and the crown to depress the latter and thereby reduce the depth of needle penetration in the fabric, said interponent being provided with a wedge-shaped inner end for entering between the stop and the crown, an adjustable stop mounted on the lever for cooperation with the foot to limit the inward movement of the interponent to thereby variably limit the downward movement of the crown, and a spring latch mounted on the lever for cooperation with the foot for retaining the interponent in its operative position.

13. The combination with a presser foot having an opening, a vertically movable crown mounted on the foot and projecting into said opening, a stop mounted on the foot to limit the upward movement of the crown, and a manually operable interponent supported on the foot and movable to a position between the stop and the crown to depress the latter.

14. The combination with a presser foot having an opening, a vertically movable crown mounted on the foot and projecting into said opening, a stop mounted on the foot to limit the upward movement of the crown, and a manually operable interponent supported on the foot and movable to a position between the stop and the crown to depress the latter, said interponent being movable in a horizontal plane and provided with a wedge-shaped inner end for entering between the stop and the crown.

15. The combination with a presser foot having an opening, a vertically movable crown mounted on the foot and projecting into said opening, a stop mounted on the foot to limit the upward movement of the crown, a manually operable interponent supported on the foot and movable to a position between the stop and the crown to depress the latter, and adjustable means for limiting the movement of the interponent and thereby variably limit the downward movement of the crown.

16. The combination with a presser foot having an opening, a vertically movable crown mounted on the foot and projecting into said opening, a stop mounted on the foot to limit the upward movement of the crown, a manually operable interponent supported on the foot and

movable to a position between the stop and the crown to depress the latter, and a spring latch for retaining the interponent in its operative position.

17. The combination with a presser foot having an opening, a vertically movable crown mounted on the foot and projecting into said opening, a vertically adjustable stop mounted on the foot to limit the upward movement of the crown, and a manually operable interponent supported on the foot and movable to a position between the stop and the crown to depress the latter.

18. The combination with a presser foot having an opening, a vertically movable crown mounted on the foot and projecting into said opening, a stop mounted on the foot to limit the upward movement of the crown, a manually operable lever mounted on the foot to swing about a vertical fulcrum, and an interponent connected to said lever and movable to a position between the stop and the crown to depress the latter.

19. The combination with a presser foot having an opening, a vertically movable crown mounted on the foot and projecting into said opening, a stop mounted on the foot to limit the upward movement of the crown, a manually operable lever mounted on the foot to swing about a vertical fulcrum, an interponent connected to said lever and movable to a position between the stop and the crown to depress the latter, said interponent being provided with a wedge-shaped inner end for entering between the stop and the crown, and an adjustable stop mounted on the lever for cooperation with the foot to limit the inward movement of the interponent and thereby variably limit the downward movement of the crown.

20. The combination with a presser foot having an opening, a vertically movable crown mounted on the foot and projecting into said opening, a stop mounted on the foot to limit the upward movement of the crown, a manually operable lever mounted on the foot to swing about a vertical fulcrum, an interponent connected to said lever and movable to a position between the stop and the crown to depress the latter, said interponent being provided with a wedge-shaped inner end for entering between the stop and the crown, an adjustable stop mounted on the lever for cooperation with the foot to limit the inward movement of the interponent and thereby variably limit the downward movement of the crown, and a spring latch mounted on the lever for cooperation with the foot for retaining the interponent in its operative position.

LOUIS G. BOWMAN.
